UNITED STATES PATENT OFFICE.

CHARLES O. MAINOR, OF OWENSBORO, KENTUCKY.

DESIGN FOR A BUGGY-SEAT.

45,428.

Specification for Design.

Patented Mar. 17, 1914.

Application filed December 15, 1913. Serial No. 806,935. Term of patent 7 years.

To all whom it may concern:

Be it known that I, CHARLES O. MAINOR, a citizen of the United States, residing at Owensboro, in the county of Daviess and State of Kentucky, have invented and produced a new, original, and ornamental Design for Buggy-Seats, of which the following is a specification, reference being had to the accompanying drawing, forming a part thereof.

The invention consists in forming the back of a buggy seat with a reverse curve as indicated at 1, having an inset panel 2 with curved corners 3 and downwardly extending points 4.

Within the inset panel a figure is provided being in the form of a conventional plant having a tall central leaf 5 with other leaves 6 upon opposite sides of such central leaf all terminating at a comparatively straight horizontal base 7.

I claim—

The ornamental design for a buggy seat as shown and described.

CHAS. O. MAINOR.
